(57) **CLAIM**

The ornamental design for a modular tooling coupler, as shown and described.

DESCRIPTION

FIG. 1 is a front perspective view of a modular tooling coupler according to a first embodiment.

FIG. 2 is a top side view of the modular tooling coupler of FIG. 1.

FIG. 3 is a bottom side view of the modular tooling coupler of FIG. 1.

FIG. 4 is a front side view of the modular tooling coupler of FIG. 1.

FIG. 5 is a back view of the modular tooling coupler of FIG. 1.

FIG. 6 is a left side view of the modular tooling coupler of FIG. 1; and,

FIG. 7 is a right side view of the modular tooling coupler of FIG. 1.

The broken lines in the drawings illustrate portions of the modular tooling coupler and form no part of the claimed design.

1 Claim, 3 Drawing Sheets
